APPARATUS FOR COATING LITHOGRAPHIC PLATES

Rudolf Fritsche, New York, N. Y.

Application July 24, 1936, Serial No. 92,387

8 Claims. (CL. 91—42)

This invention relates to an improved apparatus for coating lithographic plates, an object being to provide an improved construction wherein there will be substantially no faulty plates produced.

Another object of the invention is to provide an apparatus with means for receiving and holding sensitized material which has been sprayed or discharged from the plate when being coated with a sensitizing liquid.

A further object is to provide an apparatus for coating with a sensitizing liquid a plate and at the same time hold all foreign matter away from the plate during the coating and drying thereof.

In the accompanying drawings:

Fig. 1 is a sectional view through Fig. 2 on the line 1—1, the same disclosing the principal features of an apparatus for coating lithographic plates;

Fig. 2 is a sectional view through Fig. 1, the same being taken on the line 2—2 and disclosing an embodiment of the invention;

Fig. 3 is a horizontal sectional view through Fig. 1 approximately on the line 3—3;

Fig. 4 is a further elevation of the structure shown in Fig. 2;

Fig. 5 is an elevation of the plate coating frame shown in Fig. 2;

Fig. 6 is an enlarged fragmentary sectional view through Fig. 5 on the line 6—6;

Fig. 7 is an elevation of the clamp shown in Fig. 6;

Fig. 8 is an enlarged fragmentary sectional view through Fig. 5 on the line 8—8.

In the manufacture of lithographic plates it is necessary to apply the sensitizing liquid or solution to the plate and then to spread the solution evenly over the plate. After this has been done the solution is allowed to dry. Heretofore devices known as whirlers have been used for rapidly rotating the plate after the sensitizing liquid has been deposited thereon whereby the sensitizing material will be spread evenly over the plate and some of the material will be impelled or sprayed radially outwardly against the walls of the apparatus in which the plate has been mounted. After several plates have been coated it has been found that some of the previously sprayed material is loosened and drops on to the new plate, thus forming a defect in the plate. Various means have been provided to obviate this objection with varying successes. In the present invention means have been provided not only for whirling the plate, drying the same and confining the plate in a housing, but also for receiving and

holding any sprayed material or other matter leaving the plate so that each succeeding plate is never subjected to the possibility of having foreign matter dropped thereon.

Referring to the accompanying drawings by numerals, 1 indicates a frame of any desired kind and provided with suitable uprights and cross bars for holding the various parts hereinafter fully described. Mounted on frame 1 is a housing 2 which may be circular or may be square as shown in Figs. 1 and 4. This housing is arranged vertically and is open on one side. A suitable door structure 3 is provided for closing the opening in the housing. While various forms of door structures may be used, it has been found desirable to provide a door structure having a number of inter-engaging sliding sections 4 and 5. These groups of sections may be locked together by a suitable catch 6. The upper and lower ends of these sections are accommodated by the channels 7 and 8 as shown in Figs. 2 and 4.

It will be understood that the casing 1 is stationary but arranged within this casing is provided a member 9 which may be called a container. Container 9 is preferably circular with the axis in a horizontal plane. Container 9 is provided with a rear wall 10 and an annular peripheral wall 11 and a front wall 12 which is really a large inwardly extending flange whereby a large opening 13 is presented. Opening 13 is always in line with the opening in the casing 1 which is closed by door 3. Any desired number of rollers 14 and 15 are provided and carried by the casing 1, said rollers being positioned to prevent the container 9 from oscillating and to hold the same in a vertical plane while permitting free rotation thereof. Supporting and driving rollers 16 and 17 are arranged near the lower part of casing 1 as shown in Fig. 1, and on these rollers the container 9 is mounted. In fact, the container 9 is supported by rollers 16 and 17 while being guided by the upper rollers 18 and 19. These rollers are flanged as shown in Fig. 2 so as to help maintain the container 9 in a vertical position at all times.

A horizontally positioned driving shaft 20 is carried by the casing 1 and preferably extends loosely through the container 9 where a frame 21 is mounted. The frame 21 as shown in Fig. 5 has a central piece 22 provided with a central steady pin 23 and radiating arms 24, 25, 26 and 27. Arms 25 and 27 are provided with sliding clamps 28 which are formed as shown in Figs. 7 and 8. Each of these clamps is provided with an aperture 29 and a notch 30 having one

flat straight wall 31 against which the plate 32 is pressed by the set screw 33. Set screws 34 and 35 lock the clamp 28 at different adjusted positions along the arm 25 or the arm 27 as the case may be. Arms 24 and 26 accommodate the respective fittings 36 and each of these fittings is provided with a cross arm. Each of the cross arms is provided with a clamp 28 which functions in the same manner on the arms 31 as it does on arms 25 and 27. A set screw 38 on the respective fittings 36 acts to lock the fitting at any desired point along the respective arms 24 and 26. The various clamps 28 are adjusted to accommodate the plate 32 and may be adjusted 10 to accommodate a very large plate or a very small plate.

After the plate has been mounted on the frame 21 as shown in Fig. 2, the sensitizing liquid may be poured thereon and preferably the pouring starts at the center of the plate while the plate is rotating and the pouring instrument is moved slowly toward the periphery. After the pouring has stopped the plate continues to rotate at a comparatively high speed and thereby evenly 20 distributes the light sensitive material under the action of centrifugal force and also gravity as the plate is in a vertical plane at all times. In order to secure a proper rotation of the plate the frame 21 is secured to shaft 20 by any suitable means, as for instance the set screw 39. Shaft 20 is suitably journaled in frame 1 and carries a large pulley wheel 40 at one end. The belt 41 passes over pulley wheel 40 and also over a small pulley 42 connected to the moving part of the prime mover 43. The prime mover 43 may be an electric motor or any other suitable source of power. A sprocket wheel 44 is also rigidly secured to shaft 20 as shown in Fig. 2, and a suitable chain 45 passes over sprocket wheel 44 and also over the sprocket wheel 46 which are rigidly secured to the respective shafts 47 and 48 carrying the driving rollers 16 and 17. It will be understood that the rollers 16 and 17 drive by friction. The respective parts just described are so proportioned that the container 9 will rotate at a comparatively slow speed, while the frame 21 will rotate at a comparatively high speed. For instance, frame 21 may have fifty revolutions per minute while the container 9 may have only nine revolutions per minute or even less.

A supply of water 49 is maintained in the container 9 and as the container slowly rotates the entire inner surface of the peripheral part of the container will be moistened by its contact with the supply of water. This inner surface being continually wet and continually washed by the water 49 will receive and hold any material projected against the same. In fact, any of the light sensitive material which is projected against member 11 will be eventually washed off and held in more or less suspension in water 49 at the bottom of the container. It will be understood that the container 9 moves at such a slow speed that the supply of water 49 will always remain at the bottom of the container though it will maintain the inner peripheral surface of the container wet and will wash off any particles deposited on said surface. In this way the inner surface of the container is continually maintained clean so that it will be impossible for any particles to drop therefrom onto the plate being coated. From time to time the water 49 is drawn off through 70 the normally closed outlet 58 and discharged into

a drain 51. New and clean water is then provided. A sufficient quantity of water is provided so that the depth of water will be almost up to the bead 52.

As soon as the light sensitive material has been properly distributed over plate 32, heated air is passed over the plate so as to quickly dry the same. Various means may be provided for supplying heated air. As one example heated air from a supply pipe may be directed into the container or air at atmospheric temperature may be allowed to enter and be heated by suitable means, as for instance an electrical heater, gas heater, or the like. As shown in Fig. 1, there are provided suitable gas heaters 53 and 54 arranged in 10 housings 55 and 56. These housings are provided with suitable openings 57 and 58 which permit air to enter from the exterior of casing 2, and said air after being heated will pass up through the foraminous tops 59 and be deflected 15 by members 60 so that the air will flow substantially as shown by the arrows 61 illustrated in Figs. 1 and 2. In order to assist the proper circulation of the air, fans 62 and 63 may be used. These fans are formed and positioned to suck or draw the air upwardly and discharge the same out the top portion of the casing 2 as indicated by the arrows 64 in Fig. 2.

It will be understood that the plate is rotating at a comparatively high rate of speed while the air is circulating thereover, and consequently the light sensitive material is maintained in its uniformly spread condition while drying. When it is desired to remove the plate the prime mover 43 is stopped and the heat is turned off, though this is not absolutely necessary. However, as soon as the plate stops the door 3 is opened by unlatching the catch 6 and pushing the panels or sections 4 and 5 in opposite directions along their slides or guideways. This will fully expose the plate and the clamping screws holding the same may be loosened and the plate readily removed manually. A new plate may then be supplied and the operation repeated. If the apparatus is in use continuously there will be no chance of any deposits to be made on the inner surface of the peripheral member 11, and consequently the probability of any foreign matter dropping on any plate while the same is being coated is reduced to a minimum. Also at the end of the day's work it is only necessary to remove the water 49 and the apparatus is left clean for the night.

It will be understood that the frame 21 may be rotated at various speeds and also the container 9 without departing from the spirit of the invention. However, it is also to be noted that all of these members are arranged in vertical planes which permits a proper spreading of the coating material and also permits the water 49 to continually wash the interior peripheral surface of the container 9 so that it will always be clean. In addition, this arrangement permits the use of a large apparatus for coating a large plate while utilizing a minimum amount of floor space.

I claim:

1. In a machine for coating a plate with light sensitive material, a container of generally cylindrical form, the axis of said container extending in a horizontal plane, a plate supporting frame 70 positioned in said container and mounted to rotate in a vertical plane, said container having one side formed with a centrally positioned opening, said container being adapted to receive a supply of water, means for rigidly clamping a 75

plate on said frame, means for rotating said frame at a comparatively high speed, and means for rotating said container at a comparatively low speed.

5. 2. An apparatus for coating plates with a light sensitive material comprising a frame for holding a plate to be coated, means for rotating said frame and plate carried thereby at a comparatively high speed, a rotating container substantially surrounding said plate, said container being adapted to contain a quantity of water, and means for rotating said container at a speed comparatively slow in respect to the rotation of said frame whereby said water will continually wash the interior surface of the peripheral part of the container.

3. An apparatus for coating plates with a light sensitive material comprising a frame mounted to rotate in a vertical plane, means on the frame 20 for clamping a plate to be coated, means for rotating said frame and plate carried thereby at a comparatively high speed, a rotatable container substantially surrounding said plate and frame but not contacting therewith, said container being adapted to contain a quantity of water, and means for rotating said container at a speed 25 comparatively slow to the speed of said frame, the rotation of said container being such that said water will remain at the lowest point of the 30 container but will wash the interior surface of the peripheral part of the container as the container moves.

4. An apparatus for coating plates with a light sensitive material comprising a frame 35 mounted to rotate in a vertical plane, means for clamping a plate to be coated onto said frame, a container surrounding said frame and plate but not contacting therewith, said container being substantially formed in the shape of a drum 40 with the axis in a horizontal plane, the container being adapted to contain a supply of water, and driving means for rotating said frame and container, said driving means causing the frame to rotate at a comparatively high speed and the 45 container at a comparatively low speed, the speed of the container being such that the water therein will remain substantially at the lowermost point but will wash the interior peripheral surface of the container as the container rotates.

5. An apparatus for coating plates with a light sensitive material comprising a plate supporting frame positioned to rotate in a vertical plane, a rotatable drum surrounding said frame, means for rotating said frame at a comparatively high speed, means for rotating said drum at a comparatively low speed, and means for causing warm air to pass over the plate carried by said frame during the rotation of the frame.

6. An apparatus for coating a plate with a light sensitive material comprising a rotatable drum of relatively large diameter and shallow depth, the axis of said drum being in a horizontal plane, a casing surrounding said drum, drum driving rollers arranged within said casing acting to support and rotate said drum, means for supporting a plate in said drum, a horizontally extending shaft for rotating said plate in a vertical plane, means for rotating said plate at a comparatively high speed and said rollers so that the drum will rotate at a comparatively slow speed.

7. An apparatus for coating a plate with a light sensitive material comprising a rotatable container having an opening in one side formed 25 with a peripheral channel adapted to receive a quantity of water, a casing surrounding said container, driving rollers for supporting and driving said container so that it will rotate at a speed which will permit the water therein to remain substantially at the lowermost point while washing the walls of said channel, a frame mounted in said container in a horizontal plane, means for clamping a plate onto said frame, and means for rotating said frame and plate in 30 a vertical plane.

8. An apparatus for coating a plate with a light sensitive material comprising a rotatable container, a casing surrounding said container and provided with a door opening, a pair of 40 slideways carried by the casing adjacent the door opening, a door for closing said door opening comprising a plurality of slide panels, means within the container for supporting a plate, means for rotating said plate in a vertical plane, 45 and means for rotating said container at a speed slower than the speed of said plate.

RUDOLF FRITSCHE.
